L. F. COLE

REVERSIBLE BADGE

Filed Oct. 6, 1924

Luther F. Cole

Attorneys

UNITED STATES PATENT OFFICE.

LUTHER F. COLE, OF SPARKS, NEVADA.

REVERSIBLE BADGE.

Application filed October 6, 1924. Serial No. 742,050.

To all whom it may concern:

Be it known that I, LUTHER F. COLE, a citizen of the United States, residing at Sparks, in the county of Washoe and State 5 of Nevada, have invented certain new and useful Improvements in a Reversible Badge, of which the following is a specification.

This invention relates to badges of the character shown in my copending application 10 for patent for badges filed March 7, 1924, Serial No. 697,597.

The principal object of the present invention is to provide an improved badge which is reversible, preferably elongated in shape 15 with the pin extending longitudinally thereof so that it may be worn on a garment, or on a hat or cap with its length longitudinally of the hat band and with the pin so arranged as to prevent the badge from 20 tipping forwardly, and permitting the badge to be reversed without removing the pin from the garment or other wearing apparel. Another object is to provide an improved keeper for the pin which is shiftable so as 25 to receive the pointed end of the pin no matter on which side of the main body portion of the badge it may be disposed, and which keeper is neat in appearance, inexpensive to manufacture, and efficient in use.

Other objects and advantages of the invention will appear in the following detailed description, taken in connection with the accompanying drawings, forming a part 30 of this specification and in which drawings:

Figure 1 is an elevation looking at one face of the badge and with the pin thereof held by its keeper.

Figure 2 is a similar view but with the pin released from its keeper and the main body of the badge swung over, about a vertical axis, thus exposing the other face of the badge,—a step in reversing the badge.

Figure 3 shows another step where the main body is shifted upwardly with respect 45 to the pin.

Figure 4 shows a further step where the main body has been swung over about a horizontal axis thus exposing the first mentioned face of the main body again.

Figure 5 shows a still further step where 50 the main body has been swung about a vertical axis thus again exposing the second mentioned face, and with the pin held by its keeper.

Figure 6 is a plan view of the badge as 55 shown in either Figure 1 or Figure 5.

Figure 7 is a perspective view of a fragment of the main body and the keeper detached, to show details.

Figure 8 is an enlarged sectional view on 60 the line 8—8 of Figure 1, with the pin omitted.

In the drawings, where like characters designate like or corresponding parts, throughout the views, A designates the main 65 body of the badge, B the pin, and C the keeper.

Referring first to the main body A, it is preferably a metallic plate, elongated in shape, so as to have a major axis and a 70 minor axis, a shape conforming nicely to the band of a hat or cap. While the main body, in the example shown, is provided with relatively short and long edges 9 and 10, respectively, with the corners cut away 75 as indicated at 11, so that the plate is polygonal in shape, it is to be understood that this is merely by way of example since certain features of this invention are applicable to badges, the main body portion of 80 which differs considerably from what is shown in the accompanying drawing.

One face of the plate designated by character 12 carries certain indicia 13, while the opposite face designated by character 14 85 carries different indicia as at 15. In the example shown the badge is intended for use by employees of a railroad company, the indicia 13 indicating that when exposed to view, the user is employed as a freight brakeman, and when the indicia 15 is exposed to view, that the employee is a freight conductor. In order to further distinguish these occupations the face 12 of the plate 90 may be differently colored than the face 14. As an example, the face 12 may be silverlike, 95 such as by silver or nickel plating such face of the main body, while the face 14 may be

of gold-like color, such as by gold or brass plating such face of the main body.

In the example shown and for a purpose to be subsequently set forth, the plate is provided with an elongated slot 16 longitudinally of one of its margins, such as one of the margins 9. The plate may also be provided with parallel slots 17 adjacent an opposite margin, the slots 17 being spaced apart thus providing a web of metal 18 between the slots.

The pin is preferably connected to the main body A by the provision of an eye 19 accommodated in the slot 16 in such a manner that the pin is pivotally connected to the plate in a manner that pivotal connection may be shifted from one end of the slot 16 to the other end thereof. In the example shown, the pin B is preferably made of a continuous piece of spring wire, with the eye 19 integral with the shank 20, the shank having a pointed end portion 21. It is preferred to make the slot 16 of such a width, and the eye 19 of such a size, that when the pin is swung so as to be adjacent either of the faces of the main body A, material of the pin at the juncture 22, between the eye 19 and the shank 20, will engage the marginal portion of slot 16 opposite to margin 9, before the pointed end 21 is in operative relation to the keeper C, thus making it necessary to flex the pin B somewhat, before it may be disposed into operative relation to the keeper C. This aids in retaining the pin in proper relation to the keeper and against accidental displacement.

The keeper C is preferably made of a strip of sheet metal bent to provide opposite parallel portions 23 which, when the keeper is assembled into operative relation to the main body A, passes through the slots 17, and opposite end parallel portions 24 which limit the extent of movement of the keeper transversely of the main body A. One of the portions 23 is provided with a T-shaped slot 25 opening at one of its margins, and symmetrically disposed, so that the leading-in portion 26 of the slot may be wholly to one side or the other of the plate A and with at least one of the terminals 27 of the slot fully exposed at one or the other of the sides of the main body, as clearly shown by Figure 8. Shifting movement of the keeper is limited by engagement of the portions 24 of the keeper, one at a time, with the web 18 and it may thus be observed that if the pin B is at one face of the main body, the keeper C may be shifted so that the leading-in portion 26 of the slot 25 may first receive the pointed end portion 21 of the pin, after the pin has been flexed as hereinbefore described, and then the pointed end portion 21 may come to rest in one of the terminals 27 of slot 25. When the pin B is swung to the other face of the main body, the keeper C

may be shifted so as to receive the pointed end portion of the pin, in the manner just described, but with the other terminal 27 of the slot 25 receiving such pointed end portion. Such a keeper is neat in appearance and inexpensive to manufacture and assemble. In use, it is efficient and easily operated.

By an arrangement whereby the pin is pivotally connected to the main body adjacent one of the upper portions thereof, as shown in Figures 1 and 5, the pin may extend longitudinally of the plate, diagonally with respect to the major axis thereof thus effectively preventing the badge from tipping forwardly. This advantage may be had also in a reversible badge, by the provision of the slot 16 which also enables the badge to be reversed, without removing the pin from the garment or wearing apparel as is obvious from a consideration of the illustrations, Figures 1 to 5 inclusive, which show the steps which may be taken in reversing the badge. By this arrangement reversal of the badge may be quickly accomplished, without the necessity of making numerous perforations in the fabric or material of the garment or wearing apparel.

Changes in details may be made without departing from the spirit or scope of this invention; but,

I claim:

1. A badge comprising a plate and a pin for said plate pivotally connected thereto, and a keeper for said pin, one of said elements being slidable with respect to said plate whereby the pin may be disposed diagonally with respect to the axis of said plate and to either side of said axis when held by said keeper.

2. A reversible badge comprising a plate having indicia provided at each face thereof, and having an elongated slot adjacent one of its margins, a pin having an eye accommodated in said slot whereby the pin is pivotally connected to said plate, and a keeper for the free end portion of said pin.

3. A reversible badge comprising a plate having indicia provided at each face thereof, and having an elongated slot adjacent one of its margins, a pin having an eye accommodated in said slot whereby the pin is pivotally connected to said plate, and a keeper shiftable to receive the free end portion of said pin at either face of said plate.

4. A reversible badge comprising a plate having indicia provided at each face thereof, a pin hingedly connected at one end to said plate and swingable to a position at either face of said plate, and a keeper carried by said plate and shiftable transversely through the plate to hold said pin in either of said positions.

5. In a reversible badge, the combination

of a plate provided with spaced apart apertures, a pin swingable to either face of said plate, and a keeper for said pin including two parallel portions extending through 5 said apertures, one of said portions provided with a slot for the pointed end of said pin.

6. In a reversible badge, the combination

of a plate provided with an aperture, a pin swingable to either face of said plate, 10 and a keeper for said pin including a portion movable in said aperture and provided with a slot for receiving the pointed end of said pin at either face of said plate.

LUTHER F. COLE.
